Primary Examiner — Darcey E Gottschalk(74) *Attorney, Agent, or Firm* — Nixon Peabody LLP(57) **CLAIM**

The ornamental design for a closure, as shown and described.

DESCRIPTION

FIG. 1 is a top perspective view of a closure, showing our new design.

FIG. 2 is a front view of the closure of FIG. 1, in which the opposing side views and the back views are identical.

FIG. 3 is a bottom perspective view of the closure of FIG. 1.

FIG. 4 is a top view of the closure of FIG. 1; and,

FIG. 5 is a bottom view of the closure of FIG. 1.

The broken lines are shown for the purpose of illustrating parts of the article that form no part of the claim.
